UNITED STATES PATENT OFFICE

154,725

DESIGN FOR A TOY MUSICAL INSTRUMENT

Josephus Thompson, Covington, Ohio, assignor of one-third to Grossman Music Company, Cleveland, Ohio, a partnership

Application May 9, 1947, Serial No. 138,925

Term of patent 14 years

(Cl. D34—15)

To all whom it may concern:

Be it known that I, Josephus Thompson, a citizen of the United States, residing in the city of Covington, county of Miami, and State of Ohio, have invented a new, original, and ornamental Design for a Toy Musical Instrument, of which the following is a specification, reference being had to the accompanying drawing, forming a part thereof:

I claim:

The ornamental design for a toy musical instrument, substantially as shown.
